(57) **CLAIM**

The ornamental design for an animal water dispenser, as
shown and described.

DESCRIPTION

FIG. 1 is a perspective view of an animal water dispenser;
FIG. 2 is a front view of an animal water dispenser thereof;
FIG. 3 is a back view of an animal water dispenser thereof;
FIG. 4 is a left side view of an animal water dispenser
thereof;

FIG. 5 is a right side view of an animal water dispenser
thereof;

FIG. 6 is a top view of an animal water dispenser thereof;
and,

FIG. 7 is a bottom view of an animal water dispenser
thereof.

The broken lines illustrate portions of the animal water
dispenser that form no part of the claimed design.
